Design 243.-

Moses Pond

New Design for the top of an Air-tight Parlor Stove.

Patented Oct. 23, 1849. -

Fig. 1.

Fig. 2.

Nos. 243

Moses Pond, Boston, Massachusetts.
Letters Patent No 243. Dated Oct 23rd 1849.

The Schedule referred to in these Letters Patent and
making part of the same.

To all Persons to whom
these Presents shall come:

Be it known, that I, Moses
Pond, of Boston, in the County of Suffolk, and State of
Massachusetts, have invented or produced a new design
for the top-plate of a parlor air-tight stove, and that the
following description, taken in connection with the accom-
panying drawings hereinafter referred to, forms a full and
exact specification of the same.

The figures of the accompanying plate of draw-
ings, represent my new design. Fig. 1, is a top view of the
same, and fig. 2, is a vertical section showing the contour
of the mouldings.

There is a circular space, a a, cut out of
the centre of the oval shaped top, in which space an urn, or
other vessel, holding water for evaporation, is placed. This
space is surrounded by a raised rim, b b. On each side of
this rim, b b, there extends out a species of spear-head, c c,
raised, and cast on the flat area, d d. The circular space,
a a, and flat areas, d d, are surrounded with a cavetto mould-
ing, e e e e &c, ornamented with sunken ellipses, f f, all as
shown in fig. 1, and descending to the open work area, com-
prehended between said moulding, and the plane or flat oval
ring, g g g g. At each corner of the cavetto moulding, e e,
is a circular ring, h h h h &c., in which is cast the four
clustered arrow heads, i i i i, with sunken faces. Between
these circular rings on the ends, are cast in open work

Des. 243

the two short ornamental scrolls, K K - K K, connected together by the band at l l; and on the sides of the open-work area, and between said rings, h h - h h, are similarly cast the elongated ornamental scrolls, m m - m m, also connected by a band at, n n, as shown in fig. 1.

Beyond the oval ring, q q q q, is the ogee-shaped moulding, o o - o o, figs. 1 + 2, which is ornamented with the raised straight ribs, p p p &c, having rectangular faces, as shown in said figs. 1 + 2. The whole top is terminated by an oval ring, ornamented with egg-shaped beads, alternating with darts, so as to form what is called, the egg and dart ornament.

Having thus described my new design for the top plate of a parlor air-tight stove, I shall state my claim as follows.

What I claim as my invention, and desire to have secured to me by Letters Patent is, the combination of the several ornamented mouldings with the ornamental scrolls and clustered arrow-heads, cast in open work, and the whole forming a new design for the said top plate of a parlor air tight stove.
